UNITED STATES PATENT OFFICE.

GEORGE F. CARLILE, OF BLOOMINGTON, ILLINOIS.

RAILWAY-SIGNAL.

SPECIFICATION forming part of Letters Patent No. 289,385, dated December 4, 1883.

Application filed June 14, 1883. (No model.)

To all whom it may concern:

Be it known that I, GEORGE F. CARLILE, of Bloomington, county of McLean, and State of Illinois, have invented certain new and useful 5 Improvements in a Railway-Signal, of which the following is a full, clear, and exact description that will enable others to understand and make use of the same, reference being had to the accompanying drawings, and to letters of 10 reference marked thereon, forming a part of this specification.

This invention relates to that class of signaling devices used in connection with what is known as the "block" signal system for 15 governing the movement of trains, the road being divided into sections and the signal apparatus being so placed as to control each section in regular order.

Figure 1 is a perspective; Fig. 2, a vertical 20 longitudinal section broken away, the cap being removed; Fig. 3, a view of the signal slides and cages; Fig. 4, a horizontal transverse section in the plane xx , Fig. 1. Fig. 5 is an elevation, with one side of the outer inclosing-case removed, showing the interior; and Fig. 6 a horizontal transverse section in the plane yy , Fig. 5.

Referring to the drawings, A represents an outer inclosing-case of a rectangular form, having four equal sides; but may be of any 30 other desired form that convenience may require, the inclosing-case serving the purpose of supporting and protecting the signal devices from atmospheric changes. The lower portion of one side of the outer case consists of the 35 hinged door A', which conveniently admits of access to the interior, in order to replace or remove the signal-lamp, and for such other purposes as may be required to keep the apparatus in proper working order. The lower 40 inclosed end is provided with elongated apertures for the passage of the vertically-sliding signal-boards B B' as they are adjusted to different positions. The upper end is inclosed by the metallic ventilator cap or hood A², 45 which is perforated for the escape of the gases from the signal-lamp, placed on the inside bottom of the apparatus, as indicated by the dotted lines in Fig. 5 of the drawings. The two 50 sides of the inclosing-case, adjacent to the hinged door A', are provided with the circular openings C² C³, covered with glass, forming a bull's-eye, which reflects the light in both directions on the track. The smaller opening, B⁶, is placed in that side of the outer inclosing-case that is opposite the hinged door A', 55 said opening being covered with glass, and making proper provision for the signal-operator to observe the condition of the lamp, and whether the proper signal is being displayed. 60

The outer casing, A, is ordinarily constructed of wood and painted with any color desired. On the inside of this case is placed the metallic flue C, leaving considerable space all around between the inclosed and inclosing 65 walls for the reception and movement of the signal devices, as shown in Figs. 2 and 5 of the drawings. This flue is of a form corresponding to the outer case, and is provided with a rectangular opening closed by the vertical slide C'. The signal-lamp is placed on the inside of the metallic flue, and is thus 70 doubly protected from the inclemency of the weather. The upper end of this flue is contracted, and projects above the upper end of the outer inclosing-case into the metal cap A², which is provided with the perforated escape-tube A³, as shown in Fig. 5 of the drawings. The lower part of the metal flue C is provided with circular openings corresponding to similar openings in the outer inclosing-case, A. The adjustable signal-boards B B' are adapted to move in a vertical plane on the inside of the inclosing-case A. The lower ends of the signal-boards are provided with the circular openings B² B³, which correspond to similar openings in the outer case, A, and the inner case or metallic flue, C, the different openings being opposite each other when the signal-boards are in their normal position, as shown in Fig. 75 1 of the drawings, a white light being displayed from both sides of the apparatus. The signal board or slide B is painted red, the upper end being formed with the square open signal-box D, as shown in Fig. 3 of the drawings. The upper end of the signal-board B forms 80 one side of the square box D, which is open at both ends and incloses the metallic flue C, that forms a guide for the vertical moving signal devices. The upper end of the signal-board, forming one side of the box D, is provided with the rectangular rabbeted recess a, 85

90

95

100

the opposite side of the box being provided with a similar recess. These recesses are intended to receive and retain colored signal-sheets of glass, which slide into place from 5 the upper end. The color of the sheets of glass B⁴ in the box D is red, and that is the signal displayed when the box D is dropped down into the same horizontal plane with the signal-lamp, and is seen from both sides, the 10 signal-board being the day signal. The companion signal-board B' and the signal-box D' are of the same general construction as the box just described, the box D' being somewhat larger in order to slide over the box D, thus 15 forming a box within a box. The box D' is provided with the glass sheets B⁵, of a green shade, the day signal-board being of the same color.

These signal devices are operated and controlled by means of the cords a' a², which pass over the sheaves a³ a⁴, as shown in Fig. 2 of the drawings. The inside ends of these cords are connected to the cross-bars b b', attached to the upper ends of the signal-boxes, while the 25 opposite ends pass out through perforations in the cap A², and lead to the place where the device is to be operated from. The sheaves a³ a⁴ are journaled in the brackets b² b³, which are inserted in the under side of the bridge E, 30 which is supported by the vertical ends d d', attached to the upper end of the outer case, as shown in Fig. 2 of the drawings. By slackening on the cords the signals will drop by force of gravity, and are easily and conveniently returned to their normal position by means of the 35 controlling-cords. The signal-lamp always remains stationary, and any number of different-colored signals can be displayed from the same apparatus by simply increasing the dimensions of the outer inclosing-case and multiplying to any extent the number of signal-boxes on the inside, thus forming a double track block and train-order signal, whereby 40 one track can be blocked and the other clear, or the block-signal can be displayed for one track and train-orders for the other, or both trains blocked, or train-orders for both tracks, or train-orders for one track and the other clear, as may be required at the particular 45 time.

The apparatus is easily and cheaply constructed, the colored glass easily replaced if

broken, no parts of the device are liable to get out of order, and the different signal-glasses are protected from smoke and dust. 55

If desirable, the apparatus may be so constructed as to display the day-signal boards in a horizontal plane.

Having thus described my invention, what I claim as new, and desire to secure by Letters 60 Patent, is—

1. In a railway signal apparatus, the combination, with an outer inclosing rectangular case provided with transparent openings at the lower end and a cap and escape-tube at the 65 upper end, of a rectangular metallic flue arranged centrally on the inside of said case, said flue being provided with corresponding openings and forming a receptacle for a stationary lamp, and the square signal-boxes D D', arranged one within the other and inclosing said flue, and adapted to have a vertical movement on the interior of said case, substantially as set forth. 70

2. The combination, with the inclosing-case 75 A, of the day-signal boards B B', adapted to have a vertical movement on the interior of said case, and provided on the upper inner ends with the signal boxes or cages D D', substantially as described. 80

3. The combination, with the case A, of the signal-boards B B', adapted to project from the lower end of said case in a vertical plane, and the square signal-boxes D D', secured to the interior upper ends of said boards and 85 adapted to move simultaneously therewith, said boxes being open at the top and bottom and arranged to have an independent adjustment relative to each other for the purpose of displaying different signals, substantially as 90 set forth.

4. The combination, with the signal-boards B B', of different colors, of the signal-boxes D D', open at both ends and adapted to have an independent adjustment relative to each other, 95 the operating-cords a' a², the cross-bars b b', the sheaves a³ a⁴, the brackets b² b³, and the bridge E, all combined, arranged, and operating substantially as and for the purpose described.

GEO. F. CARLILE.
